[57] CLAIM

The ornamental design for a dispenser for surgical sutures, substantially as shown and described.

DESCRIPTION

FIG. 1 is a front elevation of a dispenser for surgical sutures showing my new design;
FIG. 2 is a rear elevation thereof;
FIG. 3 is a top plan view thereof;
FIG. 4 is a side elevation thereof;
FIG. 5 is a cross section taken on line 5—5 of FIG. 1;
FIG. 6 is an exploded perspective view; and
FIG. 7 is a perspective of a modified form of opaque reel as distinguished from the transparent reel element illustrated in FIG. 6.
